(57) **CLAIM**

The ornamental design for a sheet for a drug bag, as shown and described.

DESCRIPTION

FIG. 1 is a front view of the design;
FIG. 2 is a back view of the design;
FIG. 3 is a left-hand side view of the design;
FIG. 4 is a right-hand side view of the design;
FIG. 5 is a top plan view of the design;
FIG. 6 is a bottom plan view of the design;
FIG. 7 is an enlarged top plan view of the design;
FIG. 8 is an enlarged view of the design taken along cut lines 8-8 in FIG. 1; and,
FIG. 9 is an enlarged sectional view taken along line 9-9 of FIG. 8.

The intermittent broken line shown in FIGS. 1 and 2 represents the boundary between claimed portions of the design and the unclaimed portion of the design.

The area between the intermittent broken line and the dotted lines represents part of the sheet for a drug bag not claimed. The intermittent broken lines and the dotted lines form no part of the claim.

The line sediments shown between the solid lines and the intermittent line in FIGS. 1 and 2, and shown between the solid lines and broken line edge of the detail in FIG. 8, form part of the claimed design.
